SPOTTING BOARD

Don O. Goodwin, St. Louis, Mo.

Application August 14, 1944, Serial No. 549,383

4 Claims. (Cl. 68—240)

1

My invention relates to new and useful improvements in spotting apparatus of the type used for removing spots and stains from clothing.

Conventional spotting apparatus usually comprises a housing or cabinet upon which is mounted a spotting head. The head is essentially ovate or egg-shaped in plan so that it can properly fit various parts of the garments and its top is usually a perforate "Monel" metal sheet.

In practice, the garment to be cleaned is placed on the spotting head with the spot or stain positioned approximately centrally of the metal top. To remove the spot steam is applied downwardly on the garment. If necessary, suitable soaps or cleaning fluids may also be used. The steam passes downwardly through the perforate top and into the head from which it is discharged through a suitable exhaust pipe.

The perforate metal top is unsatisfactory in several respects. The steam particles creep along the polished metal surface underneath the garment causing the spot to spread. Moreover, impingement of the steam particles against the top causes light, glossy cloth such as silk or rayon to slide sideways thus making it difficult to clean.

In prior art spotting apparatus steam condenses in the steam supply line when the equipment is idle. Consequently, when the steam gun is first opened, a stream of water is discharged. This water must be disposed of before the cleaning operation begins. After the water is eliminated the steam is frequently too dry since steam must have a requisite humidity before it becomes effective as a cleaning agent. To supply this moisture the operator must operate a valve which admits water into the steam supply line. Both the valve for opening the steam gun and the valve for admitting water into the steam supply line are conventionally foot-operated. This requires that the operator stand on one foot placing him under considerable physical strain and creating a general health hazard. Furthermore, it is difficult to admit the exact amount of water that gives a properly humidified steam.

An important object of my invention is to provide a spotting apparatus in which the garment is held snugly against the spotting head at all times during the cleaning operation.

Another object of my invention is to provide a spotting head in which the steam will not spread underneath the cloth to diffuse the spot or stain into clean portions of the garment.

2

Still another object of my invention is to provide a spotting apparatus in which properly humidified steam is automatically maintained at all times.

5 Yet another object of my invention is to provide a spotting apparatus in which any condensate formed in the steam supply line is drained from the system so that steam is obtained immediately when the steam gun or nozzle is opened.

Other objects and advantages of my invention will be apparent during the course of the following description.

In the drawing forming a part of this specification and wherein like numerals are employed to designate like parts throughout the same,

Fig. 1 is a front elevational view of a spotting apparatus embodying my invention, parts thereof being broken away to more clearly illustrate the internal construction,

Fig. 2 is a vertical sectional view taken on the line 2—2 of Fig. 1,

Fig. 3 is a top plan view of the spotting head,

Fig. 4 is a longitudinal sectional view taken on the line 4—4 of Fig. 3,

Fig. 5 is an enlarged fragmentary sectional view taken on the line 5—5 of Fig. 1, and

Fig. 6 is a fragmentary vertical sectional view of the apparatus showing a modified means for operating the steam gun.

In the drawing, wherein for the purpose of illustration are shown preferred embodiments of my invention, the numeral 10 designates a cabinet which houses or supports the various parts and adjuncts of the apparatus. The cabinet is formed with a flat top 10a, end walls 10b and 10c, front wall 10d, rear wall 10e, and bottom 10f.

The rear wall extends substantially above the top 10a and its upper portion is fashioned with a hood or canopy 10g. The top of the canopy is flat and provided with a guard rail 10h. The top of canopy 10g is preferably about shoulder high so that a lighting fixture 10i mounted on its under side throws light upon the top 10a but is

45 shielded from the operator. Cleaning fluids and soaps may be conveniently kept on top of the canopy.

Mounted on the cabinet top 10a is a spotting head 11. The spotting head comprises an essentially funnel-shaped support 11a and a brush 11b. The brush includes a perforate base member 11c and upstanding bristle tufts 11d. The tufts are arranged close together to provide a continuous horizontal surface of bristle ends. 55 Interspersed between the tufts are perforations

11e. The brush 11b is supported on brackets 11f and is removably held in place by frictional engagement with the support. It is thus easily removed for cleaning or replacement.

The head 11 is generally ovate or egg-shaped in plan so as to readily fit all parts of the garments. The garment is placed on the spotting head with the stain or spot to be removed located centrally of the bristles 11d. The cloth lies flatly on the tufts and is held securely in place by the bristle ends. I prefer that the brush surface be slightly below the edge of support 11a so that the cloth can be released from the bristles by pulling it taut. After passing through the cloth the steam enters support 11a through perforations 11e in the back of the brush and is discharged from the system. The substances staining the cloth as well as the cleaning agents tend to flow down the bristles and onto the base 11c. There is no tendency for these contaminants or cleaning agents to spread beneath the cloth. When the brush becomes dirty it can be easily removed and cleaned.

A suction is maintained within the spotting head in order to make certain that the garment is held flatly against the bristles and to assure direct passage of the steam, cleaning agents and contaminants through the cloth and brush. Suction is created by pump 13 driven by motor 14, the suction side of the pump being connected to the spotting head by a conduit 15. As best shown in Fig. 4, the conduit is formed with a radial flange 15a which is firmly secured to the under side of the cabinet top by bolts 15b. The upper end of the conduit extends through the cabinet top and screws into the open lower end of the support 11a. The air, steam, cleaning agents and contaminants which pass into the spotting head are drawn downwardly through conduit 15 and pump 13 and discharged to a suitable disposal system through exhaust pipe 16.

Steam is supplied to the steam gun or nozzle 12 through a pipe 17, steam separator 18, pipes 19 and 20, heat exchanger 21, pipe 22, solenoid valve 23, pipe 24, T-fitting 25 and hose 26. Moisture carried into the system condenses in separator 18. Heat exchanger 21 is positioned in the suction conduit 15. It preferably comprises an elongated tubular member formed with a plurality of radial fins 21a which facilitate transfer of heat from the steam to the air in the conduit. As it flows through the heat exchanger the steam is cooled and humidified. Since a constant suction is maintained in the spotting head the steam is uniformly humidified at all times. Any excess moisture entering the system with the steam is condensed in separator 18. Very little condensate will form in heat exchanger 21 since the heat exchanger is relatively small and the steam remains therein only a short time. However, sufficient heat exchange will take place to assure a moist steam in the gun 12.

Electric current is supplied to the solenoid valve 23 through conductors 27 and 28. The valve is opened and closed by manipulation of a hand lever 29 carried by the steam gun 12 and electrically connected with the valve by cable 30.

By providing a solenoid valve in the steam supply line I am able to control the flow of steam from gun 12 by a manually operated lever carried by the gun. This arrangement relieves the operator from considerable physical strain and facilitates the entire cleaning operation.

In order to prevent steam from condensing in the apparatus when the equipment is idle I have

connected a trap 31 to pipe 19 by means of pipe 32. Any condensate forming in separator 18 immediately drains by gravity into the trap. Condensate is discharged periodically from trap 31 through pipe 33, T-fitting 34 and pipe 35. The T-fitting 25 is connected to the condensate discharge pipe by pipe 36. Any condensate forming between the heat exchanger 21 and fitting 25 drains by gravity into the discharge line 35.

10 The nipple 37 forming a part of pipe 36 is formed with a relatively small orifice 38. This orifice must be sufficiently small to resist flow of steam through pipe 36 when valve 23 is open but large enough to permit water to drain slowly from the system when it accumulates in pipe 36 above the nipple. The orifice 38 prevents steam from blowing out through pipe 36 instead of the steam gun when the valve 23 is opened.

If a plurality of spotting boards or other apparatus are connected in the discharge line 35, it is necessary to insert a check valve 39 in pipe 36, as shown in Fig. 5. The check valve seats upwardly so that a sudden increase in pressure in the discharge line will not force water or other liquids back through the steam supply lines.

15 If it is not convenient to provide an electrically operated valve in the steam supply line the solenoid valve 23 may be replaced by a mechanically operated valve 40, as best shown in Fig. 6. 30 Valve 40 is then operated by a pivoted foot pedal 41 through connecting links 42 and 43.

It is to be understood that the forms of the invention herewith shown and described are to be taken as preferred examples of the same and 35 that various changes in the size, shape and arrangement of parts may be resorted to without departing from the spirit of my invention or the scope of the appended claims.

Having thus described my invention, I claim:

40 1. A spotting board comprising a support, a brush having rigid back portion mounted on the support and bristles fastened to and upstanding from the upper face of the back portion, said bristles uniformly distributed over the area supporting the fabric during the spotting operation, and a rigid collar surrounding the bristles with its upper edge disposed in a plane spaced above the free ends of the bristles.

45 2. A spotting board comprising a tubular support having an upper open end, a brush mounted in the open end of the support with the bristles extending upwardly and their ends disposed in a plane below the level of the upper edge of the support.

50 3. In a garment spotting apparatus wherein the fabric to be treated is placed over the large end of a funnel and steam is drawn therethrough by suction means associated with the small end of the funnel, the improvement which comprises a foraminous member extending across the large end of the funnel so it is parallel to but below the plane of the rim, and upstanding bristles on the foraminous member, said bristles being distributed over the whole area of the large end of the funnel and being of such length that their tips lie in a plane parallel to but below the plane of the rim.

55 4. In a garment spotting apparatus wherein the fabric to be treated is placed over the large end of a funnel and steam is drawn therethrough by suction means associated with the small end of the funnel, the improvement which comprises an inwardly extending ledge on the funnel situated downwardly from the large end thereof, a removable foraminous member positioned with-

in the large end of the funnel so it rests on the ledge, and upstanding bristles on the foraminous member, said bristles being distributed over the whole area of the large end of the funnel so their ends support the fabric throughout that area and being of such length that their tips lie in a plane parallel to but below the plane of the rim of the funnel.
